UNITED STATES PATENT OFFICE.

SAMUEL BERGER, OF BLOOMING GLEN, PENNSYLVANIA.

RAILROAD-TIE.

1,093,877.

Specification of Letters Patent.

Patented June 2, 1914.

Application filed March 2, 1914. Serial No. 322,030.

To all whom it may concern:

Be it known that I, SAMUEL BERGER, a citizen of the United States, residing at Blooming Glen, in the county of Bucks and State of Pennsylvania, have invented certain new and useful Improvements in Railroad-Ties, of which the following is a specification.

My invention relates to improvements in railroad ties, and more particularly to an improved construction of elastic support for rails which comprises a particular construction of tie and pivoted links permitting the rails to move upon their elastic cushion, yet preventing any possibility of lateral displacement which is commonly known as spreading of the rails.

A further object is to provide an improved construction of rail which will be comparatively simple in construction, cheap to manufacture, and strong and durable in use.

With these and other objects in view, the invention consists in certain novel features of construction and combinations and arrangements of parts as will be more fully herein-after described and pointed out in the claims.

In the accompanying drawings: Figure 1 is a plan view illustrating a number of my improved ties in operative position. Fig. 2 is a view in section on an enlarged scale on the line 2—2 of Fig. 1. Fig. 3 is a fragmentary view in section on the line 3—3 of Fig. 1. Fig. 4 is a view in transverse section on the line 4—4 of Fig. 3, and Fig. 5 is a perspective view of one of the links showing a portion broken away.

1 represents my improved tie which supports at its ends, rails 2, 2, and while I have illustrated the rails of inverted T-shape in cross section, it is to be understood that the invention is not limited to any particular shape of rail as I may employ any rail having base flanges to be operatively engaged by the pivoted links 3—3 as will be herein-after explained.

The tie 1, at both ends, is recessed in its upper face as shown at 4, and the recessed ends of the tie are provided with pockets 5 in which coiled springs 6 are located and bear against the base 7 of the rail 2.

The inner walls of the recesses 4 at both ends of the tie are formed with outwardly projecting lugs 8 which are positioned over the inner base flange of the rail and limit the vertical movement of the rail.

On opposite sides of the tie at both ends, I provide the pivoted links 3. These links 3 are secured to the tie by means of bolts 9 which are projected through registering openings in the tie, and in the links at a point near the inner end of each link, so that the outer ends of the links are free to swing vertically.

Each link on its upper face at its outer end is provided with an inwardly projecting lug 10, which projects over the outer base flange of the rail, and a removable block 11 is secured to each link 3 by means of a pin 12, and overlies the inner base flange of the rail, so that the link is firmly connected to the rail and holds the latter against movement, except such as is provided by the pivotal connection of the link with the tie.

The bolts 9 are secured against longitudinal movement by nuts 13, and when these nuts are removed, the bolts may be removed and the links disconnected from the tie. The links may be disconnected from the rail by removing pin 12 so as to disconnect block 11, and hence by reason of this construction the parts may be readily assembled and taken apart as desired.

In operation, the rails are cushioned by means of the springs 6, and are permitted a certain amount of vertical movement limited by the lugs 8 and the lower walls of the recesses 4. Lateral or spreading movement of the rails is prevented by the links 3, and hence the rails can be elastically supported without danger of lateral movement.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A railroad tie having elastic rail supports at its ends, and links pivotally connected to the tie and adapted at their free ends to be secured to the rails, substantially as described.

2. A railroad tie having recessed ends, springs secured in the recessed ends and adapted to receive rails thereon, links at the sides of the tie pivotally connected at their

inner ends to the tie, and at their outer ends adapted to engage rails, substantially as described.

3. A railroad tie having recessed ends with sockets in the recessed ends, and springs in said sockets adapted to be located under the rails, links at both sides of the tie at both ends, bolts through the tie and through the inner ends of the links, the outer ends of said links having means for engagement with the base of the rails, substantially as described.

4. A railroad tie having recessed ends with sockets in the recessed ends, and springs in said sockets adapted to be located under the rails, links at both sides of the

tie at both ends, bolts through the tie and through the inner ends of the links, the outer ends of said links having means for engagement with the base of the rails, said means comprising an integral lug overlapping the outer base flange of the rail, and an inner removable block engaging the inner base flange of the rail, substantially as described.

In testimony whereof I have signed my name to this specification in the presence of two subscribing witnesses.

SAMUEL BERGER.
